UNITED STATES PATENT OFFICE.

ANDREW WALTON, OF HUNTINGTON, INDIANA, ASSIGNOR OF ONE-THIRD
TO SARAH LANGLEY, OF CHICAGO, ILLINOIS.

ADJUSTABLE CURTAIN BRACKET AND SUPPORT.

SPECIFICATION forming part of Letters Patent No. 569,898, dated October 20, 1896.

Application filed April 24, 1896. Serial No. 538,995. (No model.)

To all whom it may concern:

Be it known that I, ANDREW WALTON, of Huntington, county of Huntington, State of Indiana, have invented certain new and useful Improvements in Adjustable Curtain Brackets and Supports, of which the following is a description.

Referring to the accompanying drawings, wherein like reference-letters indicate like or corresponding parts, Figure 1 is a front view of my improved bracket with the curtain and shade in position. Fig. 2 is a similar view with the curtain and shade removed. Fig. 3 is a similar view showing the bracket extended on either side of the window-frame. Fig. 4 is an end view of the bracket as shown in Fig. 1. Fig. 5 is a section in line 5 5 of Fig. 3. Fig. 6 is a section in line 6 6 of Fig. 2 with a part broken away to show the same. Fig. 7 is a section in line 7 7 of Fig. 3. Fig. 8 is a section in line 8 8 of Fig. 3. Fig. 9 is a section in line 9 9 of Fig. 3, and Fig. 10 is a partial perspective view of the bracket proper.

Windows and the shades and curtains for them vary greatly in width, and in moving from house to house great difficulty is met with in again hanging the curtains and shades. My invention is designed to obviate this difficulty; and to this end it consists, broadly, in connecting the two brackets on the sides of the window together in such a manner that they may be moved either toward or from each other to suitably fit windows of different widths.

It also consists in constructing such side brackets with the supports both for the curtain-pole and the shade-roller.

It also consists in constructing the curtain-pole support in such a manner that it may be adjusted relative to the wall, thus positioning the pole such distance from the wall as may be desired.

It also consists in such other novel combination and construction of parts as may be shown and described, and as are more particularly pointed out in the claims, the whole being combined in the most simple and economical manner.

In the drawings, A A' represent the two parts of my extensible bracket, which are so

constructed that one part, as A', may telescope within the guides of the other, Figs. 2, 3, and 8. The slots a a', within which are located the screws B B', limit the adjustment of the two parts, as shown. The screws B B' 55 secure the parts to the window-casings. In practice I prefer to use washers b b' with the screws. Each of the parts A and A' is provided with means for securing the bracket C C'. These are preferably constructed to slide 60 tightly within guides A² A³, as shown, and as thus made may be easily disconnected and packed for shipment. A single guide would serve the purpose very well, but two guides, as shown, add materially to the stability of 65 the connection and permit of the use of the light and strong bracket C. (Shown in Fig. 4.) Each part A A' is adapted to have secured to it the support D D' for the shade-roller. I prefer for this purpose to cut and 70 bend up the lips A⁴ A⁵, to which may thus be secured the supports D D' in any preferred manner, as by rivets or bolts.

The bracket C is constructed to engage with the part A or A', as described, (the arms c c 75 being adapted to slide within the grooves A² A³,) and is preferably also provided with an extensible arm E, which may be moved upon the bracket and secured at any desired point. I prefer to engage the parts with a groove- 80 and-slide connection, as shown, when, if desired, a set-screw e may lock the parts together. The outer end of the arm E is adapted to receive and support the curtain-pole F, while the clip D supports the end of the shade- 85 roller G. (See Figs. 1 and 4.) The additional holes h h are provided for use in case it is desired to secure the parts more firmly to the window; but it will very seldom be necessary to use them for such purposes. 9c

The mode of operation is as follows: The two parts A A' are loosely secured to the head or side casing of the window, and when adjusted to the proper length the screws B B' are tightened, firmly securing the parts together and to the window. The brackets C C may then be placed in position and so secured, and the curtain-pole and shade-roller may then be placed in position in the supports. 95 100

Having thus described my invention, what I claim asnew, and desire to secure by Letters Patent, is—

1. An adjustable window-fixture consisting of a bar composed of two parts telescoping one upon the other and adapted to extend across and be secured to the window-frame; a shade-roller support secured to each end of the bar, and longitudinal grooves also located at each end of the bar, in combination with curtain-bar brackets provided with the arms, *c*, *c*, adapted to adjustably engage with the grooves in the bar, and the adjustable arm, *E*, whereby the curtain-pole supports may be adjusted both longitudinally and transversely to the curtain-pole, substantially as described.
2. A curtain-pole support consisting of base-

pieces adapted to be secured to either side of a window to the frame, and provided with one or more grooves extending horizontally parallel to the window, in combination with a curtain-pole bracket provided with an adjustable arm extending perpendicular to the window, and one or more arms adapted to adjustably engage with the grooves in the base-pieces whereby the support of the curtain-pole may be adjusted both longitudinally and transversely to the pole, substantially as described. 20 25

ANDREW WALTON.
